US00D886574S

(12) **United States Design Patent** (10) **Patent No.:** **US D886,574 S**
Thain et al. (45) **Date of Patent:** **** Jun. 9, 2020**

(54) **PACKAGE**(71) Applicant: **Apple Inc.**, Cupertino, CA (US)(72) Inventors: **Hamish Thain**, New York, NY (US);
Eric Treski, Manhattan Beach, CA (US)(73) Assignee: **Apple Inc.**, Cupertino, CA (US)(***) Term: **15 Years**(21) Appl. No.: **29/723,351**(22) Filed: **Feb. 6, 2020****Related U.S. Application Data**

(63) Continuation of application No. 29/679,273, filed on Feb. 4, 2019, now Pat. No. Des. 876,221, which is a continuation of application No. 29/621,348, filed on Oct. 6, 2017, now Pat. No. Des. 840,218, which is a continuation of application No. 29/529,588, filed on Jun. 9, 2015, now Pat. No. Des. 799,316.

Primary Examiner — Darcey E Gottschalk(74) *Attorney, Agent, or Firm* — Sterne, Kessler, Goldstein & Fox P.L.L.C.(57) **CLAIM**

The ornamental design for a package, as shown and described.

DESCRIPTION

FIG. 1 is a top front perspective view of a package showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of another package showing the claimed design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the figures show environment that forms no part of the claimed design.
